UNITED STATES PATENT OFFICE

EDWIN T. GREENFIELD, OF MONTICELLO, NEW YORK.

JUNCTION-BOX.

No. 830,317.

Specification of Letters Patent.

Patented Sept. 4, 1906.

Application filed October 28, 1904. Serial No. 230,287.

To all whom it may concern:

Be it known that I, EDWIN T. GREENFIELD, a citizen of the United States, residing at Monticello, in the county of Sullivan and State of New York, have made a new and useful Invention in Junction-Boxes, of which the following is a specification.

My invention is directed particularly to improvements in house junction-boxes for use in connection with house-wiring with armored conduits or cables; and it has for its objects, first, to devise a box which will be simple, cheap, and efficient and in which the clamping attachments may be readily applied and detached with the aid of simple tools, such as a screw-driver; second, to provide detachable means for clamping or holding the ends of inleading armored conduits or cables thereto; third, to provide simple means of clamping or securing the box itself to a gas-pipe extending from the ceiling or side wall of a room through the bottom of the box and in such manner as to adapt the same for use with gas-pipes of different diameters.

My invention will be fully understood by referring to the accompanying drawings, in which—

Figure 1 is a plan view of a junction-box embodying certain features of my improvement both for securing the ends of inleading armored conduits or cables and of securing the box itself to the ceiling or side wall of a room, a part of one of the walls of the box and of the supporting means being broken away and a part of the latter shown in dotted lines. Fig. 2 is a plan view of a modified form of the invention which is provided with external integral semicylindrical inlet-necks, showing also the ends of a flexible armored cable and an iron armored conduit as secured thereto and a sectional view of a gas-pipe to which the box is secured by one form of my novel clamping means. Fig. 3 is a sectional view taken through Fig. 2 on the line Z Z and as seen looking thereat from the bottom toward the top of the drawing in the direction of the arrows, showing in elevation a sustaining gas-pipe and a flexible armored cable as secured thereto. Fig. 4 is a detail plan view of the under side of the clamping means illustrated in Fig. 1. Fig. 5 is a detail sectional view taken through Fig. 1 on the line X X and as seen looking thereat from left to right in the direction of the arrows, a flexible armored cable being illustrated as connected to

the bottom of the box. Fig. 6 is a detail sectional view taken through the bottom of the box illustrated in Fig. 2 and upon the supposition that the opening in the bottom thereof is closed and that the lugs for supporting the box by a gas-pipe of relatively small diameter are broken out. Fig. 7 is a detail sectional view similar to Fig. 3, illustrating a modified manner of applying the clamping means exterior to the box.

In a prior application filed by me on the 24th day of October and bearing Serial No. 229,724 I have disclosed a junction-box embodying clamping means for securing the ends of inleading armored conduits or cables to inlets or openings therein through the agency of devices in the nature of a duplex clamp having at one and the same time forward motion toward the bottom of the box and lateral motion toward two conduits or cables to be clamped thereto. The present invention is directed to an improvement upon the before-mentioned box in that I have devised individual clamps for each individual armored conduit or cable and an individual clamp or supporting means for sustaining the entire box either from the ceiling or a side wall, the clamping means being generically not unlike that disclosed in the before-mentioned application, but specifically different in that, as before stated, each individual part to be connected to the box is provided with detachable clamping means of the nature indicated.

The invention will be fully understood by referring to the drawings in detail and first to Figs. 1, 2, and 5, which illustrate one modified form thereof, like numerals of reference representing like or equivalent parts wherever used throughout the specification. 1 represents the junction-box proper, which may in each instance be provided with a detachable or removable cover, secured thereto by screws in any preferred manner. The box illustrated in the drawings is designed for attachment either to the ceiling or side wall. This is effected either by screws extending directly through the screw-holes shown in the bottom thereof, or where the same is designed to be attached to a gas-pipe it may be effected through the agency of a tubular connector 2, having a flange at one end, which flange is of the contour shown in Fig. 1, the exterior curvatures thereof corresponding to the curvature of the inlet-openings for the conduits, the outwardly-extend-

ing ends of said flange being provided with screw-holes corresponding with the screw-holes in the bottom of the box, the arrangement being such that when this connector is inserted from within with the tubular part of the connector extending outward through the bottom of the box it may be secured directly to the interior thereof by the screws, as shown, and to the gas-pipe by a set-screw or in any preferred manner. The cylindrical parts of the connectors 2 may be of various internal diameters adapted to fit gas-pipes of various exterior diameters. 7 7 are inclined surfaces cast integral with the corners and bottom of the box, and 8 represents individual clamps having each an inclined surface 11, corresponding to the surface 7, and a vertical slot 12, adapted to receive an adjusting-screw 13 in a corresponding screw-hole 6 in the bottom of the box. Each clamp has an integral cylindrical neck or extension 10 with an internally-projecting ledge, said extension and ledge acting to protect the insulation of the conductors from any abrasion due to the jagged ends of the armor. In assembling the parts when wiring a building with boxes of this type the tubular part of the flanged connector 2 is inserted through the opening 4 in the bottom of the box from within and secured thereto by screws, and the externally-projecting extension at the outside of the bottom is then connected to the dependent gas-pipe by a set-screw or in any preferred manner. The curvilinear portions of the flange of the connector 2 constitute semicylindrical extensions for the inlets or openings 3 3, so that when the armored conduits or cables are entered through the inlets or openings 3 and the clamps 8 secured in the corners of the box with the cylindrical necks or extensions surrounding the ends of the armor the screws 13 are necessarily in the slots 12 and corresponding screw-holes 6 and driven home, thereby causing a wedging action between the clamps and the lateral faces of the ends of the conduits or cables and the curvilinear faces of the connector 2 in a manner which will be apparent on inspection of Figs. 1 and 5 and in such a way as to firmly grip or secure the cable and cause the cylindrical necks or extensions 10 to effectively protect the insulation of any conductors which may be drawn into or out of the box.

In the modified form of the invention shown in Figs. 2 to 6, inclusive, I provide inclined surfaces 7, extending entirely around the inner and outer edges of the box, by casting the same in the manner shown, and particularly in Fig. 3, so that the clamp shown in Fig. 4 may be secured to the inner side-wall surfaces of the box by the screws 13, extending through the slots 12 from within, and the ends of the armored cables 14 and conduits 19 firmly gripped through the lateral action of the clamps binding the same firmly against

integral external semicylindrical necks, the cylindrical extensions surrounding and fully protecting, as before, the insulation of the conductors. In this form of the invention the means for sustaining the box from the ceiling or side wall through the agency of a gas-pipe is in the nature of a clamp which is similar in its parts to the clamp illustrated in Fig. 4. This sustaining-clamp in this instance is composed of a body part 16, having a curved face on one side adapted to conform to the curvature of the gas-pipe to which the box is to be secured and an inclined face on the other side adapted to bear against a similarly-inclined face 15 on one side of a lug cast integral with the interior of the bottom of the box, (see Fig. 6,) 17 being a vertical slot and 18 an adjusting-screw, the arrangement being such that the clamping action between the box and the gas-pipe is similar to the clamping action of the parts already described, so that its operation and effect will be readily understood on inspection of the drawings. For the purpose of attaching the box to a different-sized gas-pipe I have in this instance provided the opening 4 in the bottom of the box for the largest-sized gas-pipe to which the same is to be secured, and when the box is constructed integral lugs 5 are cast therein having their inner surfaces of a curvature adapted to receive the smallest-sized gas-pipe it is designed to use, said lugs being relatively thin as compared to the bottom of the box, as will be obvious on inspection of Fig. 6, so that either one or both of the same may be broken out with pincers or a punch.

In both forms of the box illustrated in the drawings there are shown detachable disks in the side walls thereof for the purpose of admitting additional conduits therethrough, and in Fig. 6 is shown a detachable disk which is held in an opening in the bottom of the box above the lugs 5 when not broken and by the body part 16 of the clamp which is designed to hold the box when secured to a gas-pipe. With this arrangement the gas-pipe opening of the box may be concealed by this disk in the manner shown in Fig. 6 when no gas-pipe is available for supporting the same.

In Fig. 7 I have illustrated a modified form of the side-wall clamps illustrated in Fig. 2 in that the clamp 8 is arranged for attachment on the outside walls of the box, so that the clamping-surface 11 of the clamp 8 will bear against the outer inclined face 7 and force the clamp downward, thereby producing the same clamping effect upon the end of an in-leading armored conduit or cable as would be produced by the like arrangement of the corresponding parts internally disposed, as shown in Fig. 2, such a modified arrangement being the full equivalent of that disclosed in said Fig. 2.

I do not limit my invention to the especial details of construction hereinbefore described and hereinafter claimed, as a number of the features thereof might be departed from and 5 still come within the scope of the claims; nor do I limit the invention in its application or use with armored conduits or cables, as obviously the same might be applied with other well-known types of inclosed conductors or 10 cables.

Having thus described my invention, what I claim, and desire to secure by Letters Patent of the United States, is—

1. A junction-box provided with inleading 15 openings through the bottom thereof and inclined surfaces cast integral with the corners and said bottom; together with individual clamps, one for each opening, having an inclined surface corresponding to one of the 20 before-mentioned surfaces, with slots and adjusting-screws for securing said clamps in position.
2. A junction-box provided with inleading

openings for armored cables and individual clamps therefor provided with means for 25 giving to said clamps movement against the sides of the cables; together with means integral with said clamps for protecting the insulation of the cables from abrasion.

3. A junction-box having an opening in its 30 bottom for receiving a supporting gas-pipe and integral internally-projecting lugs for adapting the same for use with pipes of different diameters; in combination with a detachable closing-disk and a clamp adapted to secure the box to the pipe or to hold the disk in place so as to close the opening when desired.

In testimony whereof I have signed my name to this specification in the presence of 40 two subscribing witnesses.

EDWIN T. GREENFIELD.
